UNITED STATES PATENT OFFICE.

WILLIAM GEURINK, OF CLEVELAND, OHIO.

DESIGN FOR A FAUCET.

SPECIFICATION forming part of Design No. 32,289, dated February 27, 1900.

Application filed February 3, 1900. Serial No. 3,903. Term of patent 7 years.

To all whom it may concern:

Be it known that I, WILLIAM GEURINK, a resident of Cleveland, county of Cuyahoga, and State of Ohio, have invented and produced 5 a certain new and useful Design for Faucets; and I do hereby declare the following to be a full, clear, and exact description of the invention, such as will enable others skilled in the art to which it pertains to make and use the o same.

This invention has relation to a certain new and original design for faucets; and it consists in the novel configuration and arrangement of parts, as set forth hereinafter in the specification and illustrated in the drawings.

Figure I is a view in elevation of my faucet. Fig. II is a plan view of the top of the head portion of the faucet.

The leading characteristic of my design consists in the novel arrangement and disposition of a series of curved surfaces, producing a graceful effect and giving an ornamental appearance to the faucet.

For the sake of clearness in referring to the drawings I have divided my faucet into a base portion *a*, a body portion *b*, a neck *c*, a collar *d*, and a head portion *e*. I desire it understood, however, that there is no real line of demarcation between what I term my "base," o "body," and "neck" portions, as the curved surfaces, which give the distinctive shape to each of the portions, together constitute one and the same curved surface. The base portion *a* has a flat circular bottom which slopes 5 upwardly and inwardly to the body portion *b*, the curve at its juncture therewith being smooth and regular. The body portion *b* is

spherical in shape and is provided with a spout *b'* of the usual contour. The spout projects from the body portion in a smooth regular curve, there being no line or sharp angle to mark their juncture. The neck portion *c* is cylindrical in form and is topped by a collar *d* of slightly-larger diameter. This collar has six flat faces *d'* beveled on its surface near its lower edge, leaving a narrow strip *d''* of curved surface between each flat face. The head portion *e* is approximately globular in form and is divided into two hemispheres *f* and *g* by a raised band *h*, which extends horizontally around it at its greatest diameter. This band *h* has a milled surface. The surface of the upper hemisphere *f* is smooth and slightly flattened at its top, where it is provided with a knob or cap *f'*. A number of indentations 55 or concavities *g'* are formed in the surface of the lower hemisphere *g*. These concavities *g'* extend entirely around the said hemisphere and are arranged a short distance apart, so that a strip *g''* of the curved surface 60 of the hemisphere intervenes between each pair of concavities.

Having described and explained my invention, what I claim as new, and desire to secure by Letters Patent, is—

The design for a faucet, substantially as herein shown and described.

Signed by me at Cleveland, Ohio, this 24th day of January, 1900.

WILLIAM GEURINK.
